CLAIM

The ornamental design for a gamepad, as shown and described.

DESCRIPTION

FIG. 1 is a front elevation view of a gamepad showing the new design;

FIG. 2 is a back elevation view thereof;

FIG. 3 is a left-side view thereof;

FIG. 4 is a right-side view thereof;

FIG. 5 is a top plan view thereof, showing the gamepad in a rotated state;

FIG. 6 is a bottom plan view thereof;

FIG. 7 is a perspective view thereof; and,

FIG. 8 is a perspective view thereof, showing the gamepad in a rotated state.

The broken lines in the drawings depict portions of the gamepad that form no part of the claimed design. The surfaces between the broken lines and the full line circles also form no part of the claimed design.

1 Claim, 8 Drawing Sheets
